TWO-COLOR ATTACHMENT FOR PRINTING PRESSES

John B. Street and Otto E. Simon,
Jackson, Miss.

Application September 30, 1935, Serial No. 42,922

2 Claims. (Cl. 101—203)

This invention relates to two color attachments for printing presses. Hitherto multi-color job printing presses have been complex expensive structures for the most part and where attempts have been made to provide color appliances or attachments to job printing presses, alterations to the presses have been necessary.

The present invention provides a simple multi-color inking device including two independent inking discs carried by a base plate which may be secured to the frame of the press or the tracks on which the inking rolls run, by two set screws, the base plate being supported upon the rotary ink platen or plate of the job press by these set screws and by a pair of rollers, the pair of discs being adapted to apply two different colors of ink to the inking roll of the press, and being rotated by friction wheels bearing on the surface of the ink platen or plate of the press.

The present invention because of its simplicity of construction and efficiency in operation, and because of its ease of attachment to ordinary job printing presses, renders it of special commercial value in its intended field of use.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a top plan view of the color inking attachment embodying the invention applied to the tracks and to the rotary ink platen or ink plate of a conventional job printing press, the tracks and ink plate being shown in dotted lines.

Figure 2 is a front elevation of the parts shown in Figure 1.

Figure 3 is a side elevation of the parts shown in Figure 1 looking toward the right side of Figure 1.

Figure 4 is a detail cross sectional view taken on the line 4—4 of Figure 1.

Figure 5 is a detail cross sectional view taken on the line 5—5 of Figure 1.

Figure 6 is a detail cross sectional view taken on the line 6—6 of Figure 1.

Figure 7 is a fragmentary bottom plan view of the parts shown in Figure 4.

Referring now to the drawings in which like characters of reference designate similar parts

in the various views, 10 designates the track which guides the ink rollers of an ordinary job printing press and 11 designates the rotary ink platen or ink plate of the press, these parts being of conventional design.

In carrying out the invention a substantially square base plate 12 is cut away at two of the corners, as shown at 13. A pair of bars 14 are secured to the side edges of the plate by screws 15 and each bar is provided with a thickened 16 arcuate finger 16, best shown in Figures 3 and 4, which is adapted to be secured to the track 10 by means of screws 17. The thickened finger is provided with an offset lug 18 which is secured to the front edge of the base plate by means of a screw 19.

The base plate 12 is provided on the bottom face near the cut away rear edges 13 with depending bearing lugs 20, best shown in Figure 6, and in each lug there is journaled the shaft 20 21 of a roller 22. The rollers 22 bear upon the top surface of the ink plate 11 and coat with the set screws 17 in supporting the base plate in position upon the ink plate 11.

A pair of discs 23 are rotatably mounted in 25 openings 24 in the base plate, these discs being centered on the transverse median line of the base plate, as best shown in Figure 1, and being adapted to each supply an ink of predetermined color to a portion of the printing roll, for instance, one of the discs may supply red ink and the other may supply black ink. The periphery of each disc is provided with a groove 25 and the edge of the corresponding opening 24 in the base plate is provided with a groove 26. These 30 grooves coat in forming a ball race to receive bearing balls 27 so that the disc may rotate upon its axis with minimum friction. The bearing balls also hold each disc assembled with the base plate.

To apply the bearing balls to the ball race it will be seen by referring to Figure 5 that an opening 28 is formed in the bottom face of each disc to communicate with the ball race, the bottom face of the disc being provided with a threaded 45 boss 29 around the opening to receive a screw pin 30. When the pin is removed the balls may be fed into the ball race until the race is full and then the pin may be screwed into the boss to project into the opening 28 and prevent escape of the balls.

As best shown in Figure 4, each disc is rotated axially by means of a friction wheel 31 which bears upon the top face of the rotary ink plate 11 of the press. The roller is mounted on a shaft 55

32 which projects from the end of a plate 33 which extends across the bottom face of the base plate 12 and is secured to the plate by a pair of screws 34, best shown in Figure 7. The bottom face of the disc is recessed as shown at 35 to receive the friction wheel 31 and thus decrease the height of the base plate and friction disc above the rotary ink plate 11.

10 A groove 36 is formed in the top face of the base plate 12 and extends along the longitudinal median line of the base plate between both discs 23. The purpose of the groove is to separate the different colored inks so that they will not intermix on the base plate.

15 The ends 37 of the side bars 14 project over the cut away rear corners 13 of the base plate and provide grips by means of which the assembled base plate and discs may be transported or otherwise manipulated when desired.

20 To apply the device to a conventional printing press it is merely necessary to pass the set screw 17 through the curved fingers 16 and against the track or into a convenient threaded opening in the track or other convenient part of the frame 25 of the press. Thus no alterations are necessary. The curved fingers on the side bars of the base plate elevate the secured end of the base plate so that the fingers will cooperate with the rollers 22 in supporting the base plate and discs parallel with the ink plate of the press.

30 From the above description it is thought that the construction and operation of the invention will be fully understood without further explanation.

35 What is claimed is:

1. A multi-color inking attachment for printing presses having a rotary ink plate, comprising a base plate, means for securing the base plate at one end to the printing press, a pair of rollers

disposed on the bottom face of the base plate and adapted to coact with said means in supporting the base plate upon and parallel with the ink plate of the printing press, a pair of discs for supplying respectively different colors of ink to the ink rollers of the press, said discs being rotatable on their axes in spaced openings formed in the base plate, ball bearings supporting the discs at their peripheries in said openings, and friction wheels supported by the base plate and bearing against the underneath surfaces of the discs, said friction wheels being adapted to engage the rotary ink plate of the press and rotate the discs.

2. A multi-color inking attachment for printing presses, comprising a base plate, downwardly curved fingers secured to the base plate, set screws carried by the fingers, said fingers and set screws forming means for removable securing the base plate to a stationary portion of the printing press, a pair of rollers disposed on the bottom face of the base plate remote from the fingers and adapted to engage the ink plate of the press and coact with the fingers in supporting the base plate upon the ink plate and parallel with the ink plate, a plurality of discs adapted to supply respectively different colored inks to the inking roll of the printing press, there being openings in the base plate receiving the discs, grooves in the peripheries of the discs and in the openings forming ball races, balls in said ball races permitting the discs to rotate axially on their axes with minimum friction, and friction wheels mounted on the base plate and engaging associated discs, said wheels being adapted to engage the rotary ink plate of the press and rotate the discs.
